UNITED STATES PATENT OFFICE.

ALBERT C. CALKINS, OF LOS ANGELES, CALIFORNIA.

FURNACE.

SPECIFICATION forming part of Letters Patent No. 774,232, dated November 8, 1904.

Application filed December 8, 1902. Serial No. 134,409. (No model.)

To all whom it may concern:

Be it known that I, ALBERT C. CALKINS, a citizen of the United States, residing at Los Angeles, in the county of Los Angeles and State of California, have invented certain new and useful Improvements in Furnaces; and I do hereby declare the following to be a full, clear, and exact description of the invention, such as will enable others skilled in the art to which it appertains to make and use the same.

This invention relates to furnaces, and particularly to that class of furnaces known as "assayers" furnaces; and some of the objects of the invention are to provide a furnace of this character which will be simple and cheap in construction, while being efficient for the purpose designed.

Another object of the invention is to provide a furnace wherein liquid fuel can be employed and wherein is combined in one structure a crucible-chamber and a muffle and wherein the heating medium utilized for heating and reducing the material in the crucible may be further utilized for heating the muffle.

A further object of the invention is to provide a furnace which is so constructed that the heating medium is introduced thereto tangentially and impinges upon the walls of the furnace and is broken up by such action.

Still another object of the invention is to provide for the introduction of air into and the eduction of the same from the muffle for the purpose of oxidation.

Furthermore, an object of this invention is to provide removable portions in the walls of the furnace for the introduction or admission of air below the muffle to cool the latter when overheated.

With these and other objects in view the invention consists, essentially, in the construction, combination, and arrangement of parts substantially as more fully described in the following specification and as illustrated in the accompanying drawings, forming part of this application, in which—

Figure 1 is a side elevational view of a furnace constructed in accordance with this invention. Fig. 2 is a longitudinal central section of the same. Fig. 3 is a longitudinal central transverse section of the furnace. Fig.

4 is a sectional view similar to Fig. 2, showing the muffle-plug moved out to admit of the entrance of air into the muffle. Fig. 5 is an end elevational view of the furnace. Fig. 6 is a sectional view taken on lines 6 6 of Fig. 2. Fig. 7 is a sectional view taken on line 7 7 of Fig. 2, and Fig. 8 is a detail view of the bottom of the furnace.

Similar characters of reference designate corresponding parts throughout the several views.

Referring to the drawings, the reference character 1 designates a furnace structure, which may be of any desired size and configuration or formation and which may be constructed of any suitable material and may be inclosed by a metal casing.

The furnace is preferably constructed or composed of side walls or portions 2 of any suitable material, which may be retained in position by a metallic or other casing or sheath 4, and within said walls is located a removable bottom 5, detachably supported by a metal or other plate 6, secured in position by bolts or other devices 7, so that the bottom or floor may be readily removed when it becomes necessary to replace or renew the bottom or floor of the furnace by reason of the fluxes or slag having accumulated thereon, so as to impair the operation of the furnace, or when the contents of any of the crucibles should have been accidentally discharged thereupon.

In the side walls 2 of the furnace are preferably constructed openings 8, and along the outer edge of said opening is desirably constructed a supporting ledge or shelf 9 to receive and support the removable blocks or plugs 10, which normally close said opening, as will be readily understood.

The furnace is preferably constructed with an arch dome or roof 11 to receive the muffle 12, and said dome may be provided with an outlet 13 or passage for the escape of the products of combustion into the stack or chimney 14, preferably of metal and desirably secured around a boss or tubular extension 15 of the dome, and the stack may be retained in position by one or more tie-rods 16, Figs. 1, 3, and 5 of the drawings.

The muffle 12 is preferably open at one end

- and partially closed at the other end, with the exception of an opening 17, which communicates with a vertical passage or flue 18 in the walls of the furnace, and this flue opens into the bonnet 19, within which is formed or secured a pipe or flue 20, preferably terminating or opening within the stack and at some distance above the flue 18, substantially as illustrated in Figs. 2 and 4 of the drawings.
- 10 A supporting ledge or shelf 21 is desirably secured upon one end of the furnace, Fig. 5, and a segmental or other rim 22 is formed on or connected with the dome 11 around the muffle-opening 23, and said ledge or shelf is desirably provided with an opening or passage 24 for the admission of air into the muffle when the muffle-plug 25 is drawn out upon said shelf or ledge, as illustrated in Fig. 4 of the drawings.
- 15 One of the end walls of the furnace is cut away, as at 26, Figs. 2, 3, and 4, to receive an ignition device 27, which may be of any preferred construction that is adapted to burn liquid fuel, and by reason of the opening 26 being formed at one side of the furnace, as shown most clearly in Fig. 6 of the drawings, the heating medium is directed against the walls of the furnace and is caused to follow the walls around and to impinge thereon by
- 20 reason of the tangential injection of the heating medium, as indicated by arrows in Fig. 6 of the drawings. By means of this construction and operation the heating medium is directed against the wall of the furnace instead of directly upon or against the pots or crucibles, thereby preventing injury to the latter that is occasioned by directing the heating medium against the crucible, while the heating medium in this construction is caused to
- 25 encircle and pass around the crucible, thereby heating the same upon all sides. After heating the crucible the heating medium passes upwardly from the crucible-chamber and around the muffle in the muffle-chamber and
- 30 finally out through the opening or outlet 13 in the dome into the stack or chimney 14. The passage of the heating medium out through the stack or chimney 14 exhausts or sucks out the fumes from the muffle and flue 18, as well as facilitating the passage therethrough of the air admitted through the muffle when the muffle-plug 25 is drawn away from the end of the muffle, as shown in Fig. 4 of the drawings.
- 35 The operation of this invention will be readily understood from the foregoing description when taken in connection with the accompanying drawings and the following explanation thereof.
- 40 The ignition device, which is supplied with suitable connections with the source of fuel-supply, directs the flame or heating medium into the crucible-chamber in such a manner that the heating medium impinges upon or

45 hugs the walls thereof and encircles the pots 65 or crucibles therein, while not being initially directed against the crucible, and after heating the crucibles and the walls of the crucible-chamber the heating medium ascends against and around the superimposed muffle, which is 70 secured in the walls of the furnace, and from the muffle the heating medium passes through the outlet 13 in the dome 11 into the stack or chimney 14 by the orifice of the pipe 20, thereby exhausting or sucking out the fumes 75 and air which have risen into said pipe from the muffle, substantially as before stated.

When it is desired to introduce air into the muffle for oxidation or otherwise, the muffle-plug is drawn out and air is admitted into the 80 muffle through the opening 24 beneath said plug and passes through the muffle into the vertical flue 18, thence into the pipe 20, and finally into the stack or chimney, and the egress of the fume and air from the muffle 85 may be facilitated or increased by the cooling thereof in the flue 18 and pipe 20.

It is not desired to confine this invention to the specific construction, combination, and arrangement of parts herein shown and described, and the right is reserved to make all such changes in and modifications of the same as come within the spirit and scope of this invention.

I claim—

1. A furnace provided with a muffle-chamber and with a flue and air-passage, a muffle in said chamber in communication with said flue and a removable plug to close the end of the muffle and said passage in one position 100 and to uncover the same when withdrawn.

2. A furnace provided with a muffle-chamber and a flue and having a supporting-ledge provided with an air-passage, a muffle in said chamber in communication with said flue and a muffle-plug supported on said ledge and constructed to close said muffle and opening when in a predetermined position.

3. A furnace provided with a muffle-chamber and a flue, a bonnet upon the furnace enclosing the said chamber and flue, a pipe in communication with said flue and within the bonnet, means for admitting air through the muffle, the flue and passage and for introducing a heating medium around the muffle to 110 pass out through the bonnet and withdraw the air so admitted.

4. A furnace provided with a crucible-chamber, a muffle-chamber and a flue and having an air-inlet, a muffle in the muffle-chamber in communication with said flue and receiving air from said inlet, a bonnet around the flue and muffle-chamber and means for introducing a heating medium into the crucible-chamber to rise therethrough and through the 120 muffle-chamber and bonnet and exhausting the air passing through the muffle and flue.

5. A furnace provided with a crucible-cham-

ber, a muffle-chamber and a flue and having an air-inlet, a muffle in the muffle-chamber in communication with said flue and receiving air from said inlet, a bonnet inclosing the flue and muffle-chamber, means for introducing a heating medium into the crucible-chamber to rise therethrough and through the muffle-chamber and bonnet and exhausting the air passing through the muffle and flue and a device to close the muffle and inlet.

6. A furnace provided with a muffle-chamber and a flue and having a supporting-ledge,

provided with an air-passage, and a muffle-plug constructed to close said passage.

In testimony whereof I have signed my name to this specification, in the presence of two subscribing witnesses, at Los Angeles, in the county of Los Angeles and State of California, this 29th day of November, 1902.

ALBERT C. CALKINS.
